DESIGN FOR A COVER FOR A BOX OR CARTON

William J. McClintock, Jr., Harrisburg, Pa., assignor to Conewago Textiles, Inc., Elizabethtown, Pa., a corporation of Pennsylvania

Application February 16, 1934, Serial No. 50,747

Term of patent 3½ years

To all whom it may concern:

Be it known that I, WILLIAM J. MCCLINTOCK, JR., a citizen of the United States, residing at Harrisburg, in the county of Dauphin and State of Pennsylvania, have invented a new, original, and ornamental Design for a Cover for a Box or Carton, of which the following is a specification, reference being had to the accompanying drawing forming part thereof.

The figure is a perspective view of a cover for a box or carton showing my new design, in which the portion indicated by cross-hatching is colored bronze, the portion indicated by diagonal lines is in green and the portion indicated by horizontal lines is in blue.

I claim:

The ornamental design for a cover for a box or carton substantially as described and shown.

WILLIAM J. MCCLINTOCK, JR.
